Percy S. Bailey, Deceased,
Lucretia W. Bailey, Executrix,

by Charles T. Allen
Her Attorney.

UNITED STATES PATENT OFFICE

PERCY S. BAILEY, DECEASED, LATE OF SWAMPSCOTT, MASSACHUSETTS, BY LUCRETIA M. BAILEY, EXECUTRIX, OF SWAMPSCOTT, MASSACHUSETTS, ASSIGNOR TO GENERAL ELECTRIC COMPANY, A CORPORATION OF NEW YORK

DESIGN FOR A FLOODLIGHT

Application filed August 9, 1932. Serial No. 44,558. Term of patent 7 years.

To all whom it may concern:

Be it known that PERCY S. BAILEY, deceased, a citizen of the United States, who resided at Swampscott, in the county of Essex, State of Massachusetts, had invented a new, original, and ornamental Design for a Floodlight, of which the following is a specification, reference being had to the accompanying drawing, forming a part thereof.

In the accompanying drawing, Fig. 1 is a perspective view and Fig. 2 is a side elevation, showing the new design.

What is claimed is:

The ornamental design for a floodlight, as shown.

In witness whereof, I have hereunto set my hand.

LUCRETIA M. BAILEY,
Executrix of the Estate of Percy S. Bailey, Deceased.
